BY George D. Wright
T his ATTORNEY

UNITED STATES PATENT OFFICE.

CALVIN B. PATCH, OF GLENELLYN, ILLINOIS, ASSIGNOR TO WILLIAM H. MINER, OF CHAZY, NEW YORK.

YOKE.

1,242,850.

Specification of Letters Patent.

Patented Oct. 9, 1917.

Application filed April 13, 1916, Serial No. 90,845. Renewed August 27, 1917. Serial No. 188,494.

To all whom it may concern:

Be it known that I, CALVIN B. PATCH, a citizen of the United States, residing at Glenellyn, in the county of DuPage and

5 State of Illinois, have invented a certain new and useful Improvement in Yokes, of which the following is a full, clear, concise, and exact description, reference being had to the accompanying drawings, forming a part 10 of this specification.

This invention relates to improvements in yokes.

The object of the invention is to provide 15 a yoke having means for detachably connecting the same with a standard draw-bar, the parts being so arranged that the draw-bar and yoke may be readily disconnected without disturbing the gear.

Another object of the invention is to provide 20 a yoke of the type above indicated more particularly adapted for tandem gears.

In the drawing forming a part of this specification Figure 1 is a part longitudinal section, part side elevation of a yoke and 25 draw-bar showing my improvements in connection therewith.

Fig. 2 is a horizontal sectional view taken substantially on the line 2—2 of Fig. 1. Fig. 3 is a front end elevation of the yoke. 30 And Fig. 4 is a perspective view of the locking block.

In said drawing, 10 denotes a standard draw-bar having the usual butt 11—11, the butt being provided with a front upper 35 shoulder 12, lower front shoulder 13, upper rivet holes 14, and lower rivet holes 15. The yoke A comprises an upper arm 16, lower arm 17, rear connecting piece 18, and an intermediate thimble or post 19. At its forward end, the yoke A is provided with a rectangular, hollow hood or head having upper wall 20, side walls 121—121, and transversely extending posts or bridges 21 and 22 at the bottom thereof, said members 40 21 and 22 being spaced apart longitudinally to thereby form a rectangular opening with the side walls of the hood. The upper wall 20 of the hood is provided on its inner face with a pair of inwardly extending bosses 45 23—23 spaced apart the proper distance to engage the standardly spaced rivet holes 14. Said wall 20 is also provided with a depending, transversely extending gib or shoulder 24 arranged to engage the shoulder 50 55 12 of the draw-bar. To detachably lock the

draw-bar with the yoke, I provide a locking block B having an upwardly, extending transverse shoulder 25 at its front end, and a pair of bosses 26—26 on its upper face spaced so as to properly engage the rivet 60 holes 15. The block B is designed so that it may be inserted and removed through the rectangular opening in the bottom of the hood and in order to prevent the block B from pulling out, the shoulder 25 is extended at its ends as indicated at 27—27, said extended ends engaging in vertical grooves 28—28 in the side walls of the hood. To maintain the block B in operative position, two supporting members or plates 29 70 and 30 are provided, said plate 29 comprising a member having a horizontal portion 31 which fits over said bridging piece 21 and under the front end of the block B, and a depending flange 32 which engages the rear 75 face of said bridge piece 21 and is preferably secured thereto as by bolts 33. The rear supporting member 30 is in the form of an angle having the horizontal flange 34 thereof extending into a slot formed between 80 said bridge piece 22 and the lower arm of the yoke. The vertical flange of the member 30 fits against the inner face of the bridge piece 32 and is held in position preferably by bolts 35. It will be noted that the 85 member 30 supports the rear edge of the block B.

By the arrangement above described, it will be seen that the draw-bar and yoke always move in unison in either buff or 90 draft thereby adapting the connection to a tandem yoke. It will be noted that the block B is not only prevented from longitudinal movement by the extensions 27—27 in the grooves 28, but is also additionally 95 prevented from rearward movement by the shoulder 36 with which the rear edge of the block B engages when the block is in position. To disconnect the draw-bar, the bolts 33 and 35 are removed, the supporting 100 plates 29 and 30 are next removed, and the block B then removed downwardly through the rectangular opening in the bottom of the hood.

I claim:

1. A yoke for draft riggings having a hood at its forward end within which the butt of a draw-bar is adapted to be received, means for engaging the upper portion of a draw-bar butt, and devices for en- 110

105

- gaging the lower part of a draw-bar butt, said devices including a shouldered block insertible and removable through an opening in the bottom of the hood, and two supporting plates, one at the front and one at the rear of said block, said plates being also insertible and removable through said opening and adapted to be secured to integral portions of the hood.
- 10 2. A yoke for draft riggings having a hollow hood at its forward end, the upper wall of said hood having means for engaging the upper portion of a draw bar butt, a removable block at the bottom of the hood, said block having means for engaging the lower portion of a draw bar butt, the inner faces of the side walls of the hood being provided with vertically extending grooves and said block having lateral extensions arranged to fit within said grooves to thereby prevent forward movement of the block under draft.
- 15 3. A yoke for draft riggings having a hollow hood at its forward end, the upper wall of said hood having means for engaging the upper portion of a draw bar butt, a removable block at the bottom of the hood, said block having means for engaging the lower portion of a draw bar butt, the inner faces of the side walls of the hood being provided with vertically extending grooves and said block having lateral extensions arranged to fit within said grooves to thereby prevent forward movement of the block under draft, and means for supporting said block in operative position, comprising two removable plates arranged to support the front and rear edges of said block, respectively.
- 20

3. A yoke for draft riggings having a hollow hood at its forward end, the upper wall of said hood having means for engaging the upper portion of a draw bar butt, a removable block at the bottom of the hood, said block having means for engaging the lower portion of a draw bar butt, the inner faces of the side walls of the hood being provided with vertically extending grooves and said block having lateral extensions arranged to fit within said grooves to thereby prevent forward movement of the block under draft, and means for supporting said block in operative position, comprising two removable plates arranged to support the front and rear edges of said block, respectively.

In witness that I claim the foregoing I 40
have hereunto subscribed my name this 17th
day of March, 1916.

CALVIN B. PATCH.
